UNITED STATES PATENT OFFICE.

GEORGE L. HARRISON, OF CLEVELAND, OHIO, ASSIGNOR TO THE CLEVELAND METAL PRODUCTS COMPANY, OF CLEVELAND, OHIO, A CORPORATION OF OHIO.

METAL LEG FOR FURNITURE.

1,159,839.

Specification of Letters Patent.

Patented Nov. 9, 1915.

Original application filed July 14, 1913, Serial No. 778,877. Divided and this application filed April 23, 1914.
Serial No. 833,875.

To all whom it may concern:

Be it known that I, GEORGE L. HARRISON, a citizen of the United States, residing at Cleveland, in the county of Cuyahoga and 5 State of Ohio, have invented a certain new and useful Improvement in Metal Legs for Furniture, of which the following is a full, clear, and exact description, reference being had to the accompanying drawings.

10 This invention relates to metal legs for furniture, and particularly to a bearing plate or tread for use with such legs.

The class of furniture to which my invention is especially applicable, is shown in my 15 former application for United States Patent, Ser. No. 778,877, filed July 14, 1913, of which this application is a division.

The objects of my present invention are 20 the production of a metal leg which is very strong, yet light of weight, and which is formed at its lower end for the reception of a bearing plate or tread; and the provision of a bearing plate which may be very easily applied to the lower end of the leg; 25 which plate is so formed as to insure a smooth bearing of the plate upon a floor or other supporting surface; and to provide means for very securely fastening the plate to the leg, and for preventing angular movement 30 between the plate and the leg.

In the accompanying drawing, wherein similar reference characters designate corresponding parts throughout the several views. Figure 1 represents an elevation of the lower 35 end of a metal leg for furniture, having a bearing plate applied thereto: Fig. 2 is a central vertical section of the parts shown in Fig. 1: Fig. 3 is a bottom plan view of the leg and bearing plate: Fig. 4 is a horizontal section on the line 4—4 of Fig. 2; and Fig. 5 is a perspective of the bearing plate.

The leg 1 is of tubular formation, and, in the embodiment shown in the drawings, is substantially square in cross section. An inwardly extending flange 2 surrounds the lower end of the leg, and, being of substantially the same width throughout, leaves a square opening in the lower end of the leg.

The bearing plate 3 is of substantially the 50 same outline as the lower end of the leg, except that it has two of its diagonally opposed corners turned up to form projections 4, the projections being somewhat narrower, however, than the length of the edges from

which they rise. The bearing plate is some 55 smaller than the bottom of the leg, and its central portion is depressed and is of spherical contour, as shown at 5. This provides a smooth and comparatively small bearing surface for the plate. An aperture 6 occupies 60 the center of the depressed portion 5, and the metal surrounding said aperture is pressed upward or countersunk, so to speak, to provide a recess for the reception of the conical head 7 of the screw 8, the purpose of 65 which screw will be presently explained. The flat portion of the bearing plate between its edges and the depressed central portion 5 is adapted to bear against the underneath surface of the flange 2, and the projections 70 4 of the plate are arranged to occupy diagonally opposed corners of the square opening that is surrounded by the flange 2 and against adjacent portions of which the edges of the projections 4 bear, as shown clearly in 75 Fig. 4. The projections, thus confined within the corners of the opening in the lower end of the leg, provide very efficient locking means for preventing angular movement of the bearing plate with respect to the leg. 80

An inverted U-shaped anchor plate 9 occupies a position within the lower end of the leg 1 and has its ends 10 bearing upon the inner surface of the flange 2, at diametrically opposite points. This brings a 85 threaded hole 11, that is located at the center of the horizontal portion of the anchor plate, directly above the aforesaid aperture 6 of the bearing plate, and in a position to receive the end of the screw 8. By means of 90 this screw, the bearing plate and anchor plate may be securely drawn together and clamped to the flange 2. While it is desirable to have the anchor plate 9 made of very stiff material, it is sufficiently resilient to 95 yield under the action of the screw, and be placed thereby under a slight tension, in order that it may effectively secure the screw against turning.

Having thus described my invention, what I claim is:

1. The combination, with a tubular leg for furniture, said leg having an inwardly directed flange at its lower end portions of which meet at an angle to each other, of a 105 bearing plate which has a portion for engagement with the outer surface of said flange and a projection for confinement be-

tween angularly disposed portions thereof, an anchor plate which has portions that bear upon the inner surface of the flange, and means connecting said plates.

5. 2. The combination, with a tubular leg for furniture, the lower end of which is provided with an inwardly projecting flange having portions that meet at an angle to each other, of an anchor plate within said leg that bridges diametrically opposite portions of the aforesaid flange, said anchor plate having a threaded opening, a bearing plate for the lower end of the leg having a recess for the head of a screw and an aperture central within said recess, a screw which passes through said aperture and which has a head that is confined within the recess and is threaded into the opening of the anchor plate, and means for preventing angular movement of the bearing plate with respect to the leg, said means comprising a pair of upwardly extending lugs which are carried by said bearing plate and are adapted to occupy corners between adjacent angularly disposed portions of the aforesaid flange.

3. The combination, with a tubular leg for furniture, said leg having an inwardly directed flange at its lower end, the inner edge whereof defines an angular opening, of a bearing plate having a depressed central portion and a flat surrounding portion which bears against the outer surface of the said flange, the central portion of the bearing plate having an aperture, an anchor plate which has end portions that bear upon diametrically opposite parts of the inner surface of the aforesaid flange and which has a central threaded aperture, and a screw which passes through the aperture of the bearing plate and is threaded through the hole of the anchor plate, the bearing plate having a lug for engagement with the edge of the aforesaid flange.

4. The combination, with a tubular leg for furniture, said leg having an inwardly directed flange at its lower end, the opening defined by the inner edge of said flange being substantially rectangular, of a bearing plate which has a flat portion for engagement with the outer surface of the aforesaid flange and a projection which is adapted to be confined within one of the corners of the rectangular opening, the bearing plate having a depressed central portion and an aperture at substantially the center thereof, the material surrounding said opening being pressed upward to form a conical recess, an inverted U-shaped anchor plate having ends

which bear upon the inner surface of the aforesaid flange at diametrically opposite points, said anchor plate having a threaded opening which is arranged in axial alignment with the aperture of the bearing plate, and a screw threaded through said opening and extending through the aperture in the bearing plate and having a conical head that is contained within the conical recess of the bearing plate.

5. The combination, with a tubular leg for furniture, said leg having an inwardly directed flange at its lower end, the opening defined by the inner edge of said flange being substantially rectangular, of a bearing plate for engagement with the outer surface of the aforesaid flange which has a projection that is adapted to be confined within one of the corners of the rectangular opening, an anchor member within the leg, and means connecting the anchor member and the bearing plate.

6. The combination, with a tubular leg for furniture which is substantially rectangular in cross section, each side of the leg having a flange that is directed inwardly from its lower end, a bearing plate which is of substantially the same outline as the bottom of said leg and having a depressed central portion which is substantially spherical in contour and a flat surrounding portion which contacts with the underneath surfaces of the aforesaid flanges, said bearing plate having a central aperture, the material surrounding said aperture being pressed inwardly to form a seat, an inverted U-shaped anchor plate which has ends that are adapted to bear against the inner surfaces of certain of the aforesaid flanges, said plate having a threaded aperture which is in axial alignment with the aperture of the bearing plate, a screw which is threaded through the aperture of the anchor plate and passes freely through the aperture of the bearing plate, said screw having a head which occupies the aforesaid seat of the bearing plate, the bearing plate having diagonally opposed projections which fit in corners between adjacent flanges whereby said bearing plate is held against relative angular movement with respect to the leg.

In testimony whereof, I hereunto affix my signature in the presence of two witnesses.

GEORGE L. HARRISON.
